INFANT RESTRAINER FOR FLUOROSCOPIC EXAMINATION AND THE LIKE

David L. Tayman, Arnold, Md.; by Nancy E. Tayman, Terrace Gardens, Arnold, Md. 21146, administratrix of David L. Tayman, deceased

Filed June 21, 1971, Ser. No. 155,383

Term of patent 14 years

Int. Cl. D24—02

U.S. Cl. D83—1 H

FIG. 1 is a perspective view of the infant retractor for fluoroscopic examination and the like showing my new design;

FIG. 2 is a plan view of the retractor;

FIG. 3 is a side elevational view of the retractor; and FIG. 4 is an end elevational view of the retractor.

What is claimed is:

The ornamental design for an infant retractor for fluoroscopic examination and the like, as shown.
